UNITED STATES PATENT OFFICE.

RUDOLPH WEHR, OF NEW YORK, N. Y.

INTERNAL-COMBUSTION ENGINE.

1,252,753.

Specification of Letters Patent. Patented Jan. 8, 1918.

Application filed April 13, 1916. Serial No. 90,911.

To all whom it may concern:

Be it known that I, RUDOLPH WEHR, a subject of the King of Hungary, and a resident of the city of New York, in the county 5 of New York and State of New York, have invented certain new and useful Improvements in Internal-Combustion Engines, of which the following is a specification.

The present invention relates to internal 10 combustion engines, more particularly to rotary valves for use in conjunction with such engines.

With valves of this type serious troubles 15 have been experienced heretofore, to wit: Due to the continuous rotation or oscillation, as the case may be, of the valve either the valve itself or its valve seat wears out, whereby the fluid-tight joint between the valve and its chamber is destroyed with a 20 result that the compression in the combustion chamber of the cylinder is materially lowered.

One of the main objects of the present invention is to obviate this defect, by providing 25 a lining for the valve chamber, which automatically adjusts itself to compensate for the wear thereof.

With this and other objects in view, which 30 will more fully appear as the nature of the invention is better understood, the same consists in the combination, arrangement and construction of parts hereinafter fully described, pointed out in the appended claims and illustrated in the accompanying drawings, 35 it being understood that many changes may be made in the size and proportion of the several parts and details of construction within the scope of the appended claims without departing from the spirit or sacrificing any of the advantages of the invention.

One of the many possible embodiments of 40 the invention is illustrated in the accompanying drawings, in which:

Figure 1 is a vertical central section taken 45 through a portion of an internal combustion engine having the improvement mounted thereon; Fig. 2 is a section taken on line 2-2 of Fig. 1; Fig. 3 is a section taken on line 3-3 of Fig. 1; and Fig. 4 is a similar section taken through the lining alone.

The invention is described herein as applied to a single cylinder internal combustion engine of the four cycle type, but it 55 is obvious that it may be used in connection with other types just as well.

Referring now to the drawings, the numeral 10 indicates the working cylinder of the engine, provided for the well known purpose with a water jacket 11. In this cylinder reciprocates a piston 12 of any suitable construction. For igniting the successive combustible charges supplied to the cylinder a sparking device 13 of any suitable type is provided. In the top of the cylinder 60 is formed an elongated port 14, from which leads an upwardly extending tubular member 15, that is of oblong cross section, corresponding to that of the port 14. This tubular member is cast integral with the engine cylinder and is open at its top. Upon the head of the cylinder is mounted a valve-casing 16, the longitudinal axis of which is disposed parallel to the longer axis of the port 14. The side walls of this casing, 65 denoted by the numeral 17, extend vertically and are provided one with an inlet 18 and the other one with an outlet 19. The base 20 of the valve-casing is circular in configuration and rests upon the cylinder head, 70 a suitable packing 21 being interposed for the well known purpose. In this base is formed an annular recess 22, in which is seated a disk-shaped extension 23 of a valve-casing lining 24. On this disk-shaped extension of the lining are mounted packing 75 rings 25, which bear against the vertical face of the recess 22, the height of the extension 23 being smaller than that of said recess. The lining is provided with vertically 80 extending sides 26, snugly fitting the inner faces of the side walls of the valve-casing, said sides being connected by a semi-cylindrical portion 27, corresponding substantially in shape to the configuration of the 85 top portion of the valve-casing. In the lining are formed apertures 28 and 29, registering with the inlet 18 and outlet 19, respectively, of the valve casing. There is also formed in the said lining an aperture 90 30, in which is seated the tubular member 15. The semicylindrical portion 27 of the lining does not contact with the inner face of the top portion of the valve-casing, but is disposed at a distance therefrom. The 95 semi-cylindrical portion 27 is provided with a bolt 31, projecting through an opening 32 in the top of the valve-casing. This bolt is screw threaded at its free end, as shown at 33, and with these threads mesh those of 100 34. Upon the bolt is coiled a spring 35, one end of which abuts against the said

nut and the other one against the top of the valve-casing. The tendency of this spring is to raise the lining 24.

A rotary valve 36 is disposed within the lining. The spindles 37 and 38 of this valve are journaled in bearings 39 and 40, respectively, upon the heads of the valve-casing. This valve is provided with an arc-shaped passage 41, the width of which corresponds to that of the port 14 in the cylinder head and also to that of the inlet and outlet in the valve-casing. The length of this passage corresponds to that of said port and also to that of said inlet and outlet. 10 The valve is driven from the crankshaft of the engine by any suitable means, such means including a member mounted upon the spindle 38 (not shown). The valve rotates at a speed half of that of the crank-shaft, or in other words while the crank-shaft makes two revolutions the valve completes one turn, as usual in four cycle internal combustion engines. The valve seat is formed upon the lining of the valve-casing, 15 more particularly in its lower portion 42, said portion being disposed between the lower edges of the apertures 28 and 29 in the said lining, and this seat is the only portion of the lining at which the valve contacts 20 therewith, as clearly appears from Fig. 1 of the drawings. Upon the inner face of the semi-cylindrical portion 27 of the lining is mounted a packing strip 27', which contacts with the valve throughout the length of the latter. 25

A lubricating system is provided for the valve seat. For this purpose there is formed in the lining a channel 43, that communicates through a nipple 44 with a feed pipe. 30 From this channel lead passages 45 up to the valve seat and passages 46 down toward the cylinder head. There is furthermore provided a passage 47, which leads from the channel 43 to the aperture 30 in the lining, 35 the walls of said aperture being spaced from the tubular member 15, and the open top of the latter being disposed a slight distance from the peripheral portion of the valve. 40 The lining of the valve-casing is, preferably, made of gray iron, which is somewhat softer than the material of which the valve is formed. 45

The operation of this device is as follows: 50 Let us suppose that the lining of the valve-casing is in the position shown in the several figures of the drawings. The spring 35 causes the said lining to contact throughout the entire area of its seat portion with the valve, thereby forming an airtight closure so as to prevent the pressure in the working chamber of the cylinder from being lowered by leakage. As, during use, the valve seat wears off, the spring causes the lining 55 to rise and to make continuously an airtight

closure. It is for this reason that the height of the extension 23 of the lining is smaller than the height of the recess 22 in the base of the valve casing, and also is it for this reason that originally there is a space left 70 between the top of the valve-casing and the semi-cylindrical portion 27 of the lining. The packing strip 21 is provided to prevent the inlet 18 and the outlet 19 of the valve-casing from communicating through the 75 space between the semi-cylindrical portion 27 of the lining and the valve. As the lining rises, gases would be apt to escape through the recess 22 in the base 20 of the valve-casing. The packing rings 25 on the extension 80 23 of the lining, however, prevent such occurrence.

The pressure in the working chamber acts through the passage 47 on the lubricating material in the channel 43, and forces lubricating material through the passages 45 onto the valve seat and through the passages 46 onto the cylinder head. The lubricating material on the cylinder head is then forced toward the packing rings 25 to keep the 90 same well oiled so as to permit of a sliding motion of the lining, if required by the wearing off of the seat. 95

From the foregoing it appears that the invention consists, broadly speaking, in providing a slidable valve seat that is kept continuously and automatically in contact with the rotary valve of an internal combustion engine in order to provide an airtight closure for the working chamber thereof. The semi-cylindrical portion 27 of the lining is provided for no other purpose but to constitute a support for the means which cause the valve seat to rise automatically in the manner above described. It is obvious, however, that the spring 35 need not be applied to the top of the valve-casing, in which case, of course, the semi-cylindrical portion 27 of the lining could be done away with. 100

What I claim is:—

1. In an internal combustion engine, the combination with a valve-casing, of a rotary valve arranged therein, a lining for said casing shiftably arranged in the latter and having a concave portion forming the seat for said valve and completely surrounding the latter, and means engaging said lining and said casing for causing a continuous contact between said seat and said valve. 110

2. In an internal combustion engine, the combination with a valve casing, of a rotary valve arranged therein, a sleeve shiftably arranged in said casing and having a concave portion forming the seat for said valve, said sleeve surrounding completely 115 said valve, and means engaging said sleeve and said casing for causing a continuous contact between said seat and said valve. 120

3. In an internal combustion engine, the combination with a valve casing, of a ro- 125

tary valve arranged therein, a sleeve shiftably arranged in said casing and having a concave portion forming the seat for said valve, said sleeve surrounding completely 5 said valve, and means disposed outside of said casing engaging said sleeve and said casing for causing a continuous contact between said seat and said valve.

4. In an internal combustion engine, the 10 combination with the cylinder of the engine having a port, of a valve-casing thereon provided with an inlet and outlet, a rotary valve arranged in said casing having means for periodically opening and closing communications 15 between said port and said inlet and outlet, a shiftable valve seat within said casing, and means for causing continuous contact between said seat and said valve, said valve seat being provided with a 20 channel containing a lubricant communicating through passages with the working face thereof, said channel communicating also with the port in said cylinder, substantially as and for the purpose specified.
- 25 5. In an internal combustion engine, the combination with the cylinder of the engine,

of a valve-casing thereon, a rotary valve arranged in said casing, a shiftable valve seat within said casing, means for causing a continuous contact between said valve and said 30 seat, said valve seat being provided with a channel containing a lubricant communicating through passages with the working face thereof, said channel communicating also through a passage with the working chamber 35 of said cylinder.

6. In an internal combustion engine, the combination with the cylinder of the engine, of a valve-casing thereon, a rotary valve arranged in said casing, a valve seat within 40 said casing, said valve seat being provided with a channel containing a lubricant communicating through passages with the working face thereof, said channel communicating 45 also through a passage with the working chamber of said cylinder, substantially as and for the purpose specified.

Signed at New York, in the county of New York, and State of New York, this 27th day of March A. D. 1916.

RUDOLPH WEHR.
